UNITED STATES PATENT OFFICE

147,805

DESIGN FOR A DOUBLE-BREASTED COAT

John L. McGeary, San Francisco, Calif.

Application November 18, 1946, Serial No. 134,855

Term of patent 7 years

(Cl. D3—4)

To all whom it may concern:

Be it known that I, John L. McGeary, a citizen of the United States and a resident of San Francisco, in the county of San Francisco and State of California, have invented the new, original, and ornamental Design for Double-Breasted Coat, of which the following is a specification.

Reference is had to the accompanying drawing forming part thereof, in which:

Figure 2 is a similar view thereof illustrating the outer overlapping part or fly turned outward to show the inner fly.

I claim:

The ornamental design for a double-breasted coat, as shown.

JOHN L. McGEARY.
